UNITED STATES PATENT OFFICE.

FRANK H. FERAUD, OF GRANITE CITY, ILLINOIS.

PHONOGRAPH-LAMP.

1,300,363.

Specification of Letters Patent. Patented Apr. 15, 1919.

Application filed August 2, 1917. Serial No. 184,068.

To all whom it may concern:

Be it known that I, FRANK H. FERAUD, a citizen of the United States, residing at Granite City, Illinois, have invented a certain new and useful Improvement in Phonograph-Lamps, of which the following is a full, clear, and exact description, such as will enable others skilled in the art to which it appertains to make and use the same.

10 This invention relates to machines for reproducing sound, and particularly to machines of the type that are commercially known as phonographs and graphophones.

The main object of my invention is to 15 provide a phonograph lamp, namely, a combined lamp and sound reproducing machine which is so constructed that the record can be applied to and removed easily from the turntable or rotatable record support of the 20 machine in practically the same manner that records are applied to and removed from phonographs and graphophones of the kind now in general use.

Another object is to provide a device of 25 the character referred to that presents a neat and ornamental appearance and which is so constructed that standard large-sized records can be used in same. Other objects and desirable features of my invention will 30 be hereinafter pointed out.

Figure 1 of the drawings is a vertical sectional view of a combined lamp and sound reproducing machine constructed in accordance with my invention; and

35 Fig. 2 is a similar view, illustrating a modification of my invention.

Referring to Fig. 1 of the drawings which illustrates one form of my invention, A designates the standard of an electrolier or electric table lamp, B designates the shade of said lamp and C designates one or more lighting units, preferably incandescent lamp bulbs, that are arranged inside of the shade B. The phonograph or sound reproducing machine, which may be of any preferred type, is arranged inside of the shade B and is supported either directly or indirectly by the standard A of the lamp. The machine shown in Fig. 1 of the drawings comprises 45 a motor D, preferably electrically driven,

a tone arm or reproducer arm E and a turntable or rotatable record support F on which the record (not shown) is mounted when the machine is in operation, said reproducer arm being equipped with a reproducer that 55 is provided with a stylus or needle that acts upon the record. The motor D is suspended from the underside of a horizontally-disposed plate 1 which is carried by brackets or upright supports 2 that are connected 60 to a laterally-projecting flange 3 on the upper end of the standard of the lamp, and the turntable or record support F is secured to a vertically-disposed shaft 4 that is driven by the motor D.

In the form of my invention shown in Fig. 1 the standard A of the lamp is so constructed that it serves as the horn of the sound reproducing machine, said standard being hollow and provided at its lower end 70 with a flared portion 4^a that rests upon the table or structure on which the lamp is mounted. The reproducer arm E is connected with the hollow standard A of the lamp by means of a conduit 5, and the flared portion 4^a of the standard is provided with openings 6 of any preferred form or outline so as to permit the sound to escape from the horn formed by the standard A. If desired, inclined baffles 7 can be arranged inside of 80 the standard A.

The shade B of the lamp is preferably so constructed that the upper portion of same can be raised so as to permit the records to be easily applied to or removed from the 85 turntable F of the machine. One convenient way of constructing said shade is to form it in two parts, the lower part being secured to the plate 1, and the upper part B' being connected to the plate 1 by a hinge 8 so as to permit said upper part B' to be swung upwardly. If desired, an electric lamp bulb 9 can be arranged on the inner side of the top portion B' of the shade, so as to illuminate the turntable F of the sound reproducing machine during the operation of applying or removing a record, and also illuminate the top portion of the shade if it is made of transparent or translucent material. Electrical conductors 10 that supply current 100

to the motor D are preferably led upwardly to the motor through the standard A of the lamp and branch conductors 11 are led from the supply conductors 10 to the lighting units C and to the electric lamp bulb 9 in the top portion B' of the shade. If desired, the top portion B' of the shade can be provided with a ball, knob or projection 12 of any other desired form that serves as a handle for raising the top portion of the shade and also as an ornament for the shade.

In the form of my invention shown in Fig. 2, the horn of the sound reproducing machine is formed by the lower portion of the shade B² and by a substantially inverted, frustoconical-shaped member 13 that is arranged inside of the shade and spaced away therefrom. In this form of my invention the top portion B³ of the shade of the lamp and the plate 1 form the sound box of the sound reproducing machine and the plate 1 is provided with holes or openings 14 through which the sound can escape into the horn formed by the member 13 and the lower portion B² of the shade of the lamp. The member 13 is preferably formed of opaque material and the lighting units C' of the lamp are arranged on the exterior of same. The standard A of the lamp can either be solid or hollow and it is provided with a base 15. The plate 1, instead of being carried by brackets, as in the form of my invention shown in Fig. 1, is mounted directly on integral arms 2^a on the standard A. The chief desirable characteristic of a combined lamp and sound reproducing machine of the construction above described is that the record can be applied to or removed from the turntable F easily, owing to the fact that said turntable is arranged inside of a movable or removable top portion of the shade of the lamp. Furthermore, as the motor, turntable and tone arm are all arranged inside of the shade of the lamp, the standard of the lamp can be of the same dimensions generally used in electroliers, and the turntable of the machine can be made large enough to carry large-sized standard phonograph records.

It is, of course, immaterial, so far as my invention is concerned, whether the lamp be of the table type or of the type that stands on the floor of a room, and the particular details of construction of the standard and shade of the lamp and the mounting of the sound reproducing machine are also immaterial, as my broad idea consists of a combined lamp and sound reproducing machine in which the turn table or rotatable record support is arranged inside of the shade of the lamp. It is preferable to mount the motor of the machine adjacent the upper end of the standard of the lamp, so that it will be in close proximity to the turntable, and

it is also preferable to use a shade whose lower portion is fixed or stationary and whose upper portion is movable or removable, but neither of these features are essential to the successful operation of my device.

Having thus described my invention, what I claim, and desire to secure by Letters Patent, is:

1. A device of the character referred to, consisting of a lamp provided with a shade, and a sound reproducing machine provided with a turntable or record support that is arranged inside of said shade, said shade having a movable top portion that can be shifted into an inoperative position when a record is being applied to or removed from said turntable.

2. A device of the character referred to, consisting of a lamp provided with a shade, and a sound reproducing machine comprising a motor and a turntable or record support, both of which are arranged inside of said shade, said shade comprising a top portion that can be moved into a position to permit a record to be applied to or removed from said turntable.

3. A device of the character referred to, comprising a lamp provided with a standard and a shade, a sound reproducing machine comprising a motor that is carried by said standard, and a rotatable record support operated by said motor and arranged inside of the shade of the lamp.

4. A device of the character referred to, consisting of a lamp provided with a standard and a shade, a supporting plate carried by said standard, the top portion of the shade of the lamp being hinged to said supporting plate, a sound reproducing machine comprising a motor arranged on the underside of said supporting plate, and a turntable or record support operated by said motor and arranged above said supporting plate.

5. A device of the character referred to, consisting of a lamp comprising a standard, a lighting unit carried by said standard, a supporting plate arranged adjacent the upper end of said standard, a shade for said lamp comprising a lower portion connected to said supporting plate and a hinged top portion carried by said plate, and a phonograph provided with a turntable or record support that is arranged above said supporting plate and which is normally hidden from view by the top portion of said shade.

6. A device of the character referred to, consisting of a lamp comprising a standard, a shade, a horizontally-disposed supporting plate on said standard that divides said shade into an upper portion and a lower portion, the upper portion being hinged to said plate, means for illuminating the up-

per portion and lower portion of said shade, and a phonograph carried by said standard provided with a turntable or record support that is arranged above said plate.

5 7. A device of the character referred to, consisting of an electric lamp and a phonograph combined as a single unit, the turn-

table or record support of the phonograph being arranged inside of the shade of the lamp and the standard of the lamp being 10 constructed to serve as the horn of the phonograph.

FRANK H. FERAUD.
